UNITED STATES PATENT OFFICE.

JAMES F. RALEIGH, OF CHICAGO, ILLINOIS, ASSIGNOR TO PINES MANUFACTURING COMPANY, OF CHICAGO, ILLINOIS, A CORPORATION OF DELAWARE.

SHUTTER APPARATUS FOR RADIATORS.

Application filed December 22, 1923. Serial No. 682,219.

My invention relates to a shutter apparatus for controlling the flow of air through the radiator of an internal combustion engine. An apparatus of this kind is particularly useful when used in connection with an internal combustion engine constituting the power plant of an automotive vehicle.

The specific embodiment of my invention herein disclosed comprises shutters which, during the operation of the engine, open to increase the rate at which heat is radiated by the radiator, but which quickly return to closed position when the engine ceases to operate. As will hereinafter appear, I prefer to operate the shutters by fluid under pressure, preferably air, which may be supplied from a pump actuated by the normal variations in fluid pressure within one of the cylinders of the engine with which the apparatus is associated. The fluid under pressure operates the shutters through the agency of a fluid pressure responsive device, which, in turn, is controlled by a valve actuated by a thermostat which is responsive to changes in engine temperature, the thermostat preferably comprising portions in direct contact with the core of the radiator.

The foregoing and other features, objects and advantages of my invention will more fully appear from the following description wherein reference is made to the accompanying drawings, in which

Figure 1 is a diagram illustrating various elements of my improved apparatus and the fluid pressure connections between the same;

Figure 2 is a fragmentary rear elevational view of a detachable type of radiator shutter apparatus embodying my present invention; and

Figure 3 is a sectional view taken on the line 3—3 of Figure 2, and looking in the direction indicated by the arrows.

Referring first to Figures 2 and 3, it will be seen that I have illustrated a detachable shutter apparatus which in many of its structural characteristics is, or may be, substantially identical with the shutter apparatus described and claimed in my Patent No. 1,458,593, dated June 12, 1923. Such a detachable shutter apparatus preferably includes a sheet metal shell comprising a marginal flange 4, a fenestrated forwardly dished central portion 5, a shutter frame which is suitably mounted within the shell,

55 pivotally mounted shutters 7—7 adapted to control the flow of air through the shell fenestration, a spring 8 which cooperates with shutter operating bar 9 normally to hold the shutters in the closed position illustrated in the drawings, and a link 10 which 60 serves to open the shutters against the tension of spring 8 when a bell crank lever 11 pivoted to the shutter frame is moved in a clockwise direction (Fig. 2). The shell flange 4 is beaded at its outer edge to provide a rearwardly opening channel which receives a cushioning strand 12.

Persons skilled in the art to which my invention relates and familiar with the construction illustrated in my prior patent 70 aforesaid will understand that the attachment shell is, or may be, applied to an automobile radiator by long, slender bolts (not shown) which extend through the radiator core and through apertures 13—13 in the 75 marginal flange of the shell, said bolts serving to clamp the outer edges of the shell flange tightly against cushioning strip 12 and to clamp the latter tightly against the radiator front in such a way that all, or a 80 very large part of all, of the air which passes through the radiator core must find its way through the shell fenestration controlled by shutters 7—7.

As thus far described, the device of my 85 present invention need not differ substantially from a well-known radiator shutter attachment now in widespread use upon American automobiles. I shall now describe those parts of the apparatus which 90 are the salient features of the present invention.

Disposed within the forwardly dished central portion of the attachment shell and conveniently mounted upon the shutter frame 95 6 is a cylinder 14 within which a piston 15 is adapted to reciprocate, the rod 16 of said piston being operably connected with the bell crank 11 hereinbefore mentioned. If desired, cylinder 14 may contain a spring 17 100 which tends to move piston 15 to the left (Figs. 1 and 2). It will be understood that spring 17 supplements spring 8. I may dispense with either of these springs if desired.

Disposed within the upper part of the forwardly dished central portion of the attachment shell is a thermostatically actuated

valve mechanism comprising a member 18, preferably formed of metal which is a good conductor of heat and which comprises a flange 19 of considerable area, which is 5 adapted to lie against, or in immediate proximity to, the forward face of the radiator core. Member 18 may be held in position by being secured to the upper portion of the shutter frame 6. Formed in that face 10 of the member which lies nearest the radiator core is a recess 19', in which is located a thermostat 20. The thermostat herein shown is of the well-known bi-metal type and is so constructed that its free end moves away 15 from the radiator core in response to increased temperature. The free end of the thermostat embraces, or is otherwise operably connected with, a valve element 21, which is adapted to reciprocate in a cylindrical bore formed in a boss 22 which may constitute an integral part of the member 18. When in the position illustrated in Fig. 1, the valve member 21 precludes communication between ports 23 and 24 formed in 20 the aforesaid boss 22, but it will be noted the said valve member 21 is provided with an annular groove 21^a adapted to afford communication between the ports 23 and 24 when the thermostat responds to a predetermined 25 rise in temperature. Port 23 is connected through a metal or other suitable conduit 25 with the cylinder 14 and port 24 is connected through a similar conduit 26 with a suitable air pump 27 which I shall presently describe in detail.

It will be noted that cylinder 14 is provided with a relatively small opening 28 through which, when open, air under pressure in cylinder 14 may escape to a vent 29. 40. The opening 28 is adapted to be closed by a reciprocating cone valve 30 which responds to fluid pressure delivered thereto through a conduit 31 which constitutes a branch of the conduit 26 which affords communication 45 between the port 24 and the air pump 27. Thus, it will be understood, the valve 30 seats and closes the opening 28 when a pressure greater than atmospheric exists in the conduits 26 and 31, but is adapted to 50 permit air under pressure to escape from cylinder 14 when atmospheric pressure exists in the conduits 26 and 31.

The pump 27 may consist of a relatively small cylinder 32 provided with an externally threaded hollow stem 33 adapted to be threaded into the upper part of one of the engine cylinders indicated at 34 and to afford communication between the engine and pump cylinders. The piston which operates in the engine cylinder 34 is illustrated at 60 35. The pump cylinder 32 is provided with an air port 36, and operating in said pump cylinder is a piston 37 which is adapted to move downwardly to admit air to the upper 65 part of the pump cylinder when, during any

intake stroke of piston 35, a pressure substantially less than atmospheric is established in cylinder 34. During each compression stroke of engine piston 35 the pump piston 37 moves upwardly to cover port 70 36 and to deliver air into conduit 26. If desired, conduit 26 may be provided with a check valve seating against pressure from pump cylinder 37, but such a check valve is ordinarily not necessary due to the fact 75 that when the automobile engine is running the pump can easily maintain a substantial pressure within conduits 26 and 31, notwithstanding the absence of such a check valve.

Describing the operation of the apparatus 80 of my invention, it may be assumed that the engine is at rest and that the several moving parts of the apparatus occupy the positions illustrated in the drawings. As soon as the engine starts to operate, the pump 85 27 likewise operates and creates an air pressure greater than atmospheric in the conduits 26 and 31. The cone valve 30 thereupon seats. As the temperature of the engine increases, the temperatures of the cooling water and radiator core likewise increase, with the result that the cylindrical valve member 21 is moved toward the position where it affords communication between 90 ports 23 and 24. As soon as such communication is established, the air pressure created by pump 27 is transmitted to cylinder 14, moving the piston 15 against the action of springs 8 and 17 and opening the shutters. Since that portion of valve member 21 which 95 affords the annular groove 21^a is frusto-conical in shape, the air which is delivered to cylinder 14 is admitted gradually, with the result that the shutters are not opened with undue suddenness. Provided the engine continues to operate, the shutters remain open until the temperature of the radiator core has fallen to such a degree that the thermostat 19 has moved valve 21 to a position 100 where it shuts off communication between ports 23 and 24. When this occurs the springs 8 and 9 move the shutters toward their closed position as fast as the air trapped in cylinder 14 can escape around the piston 15. The piston 15 need not fit the cylinder very tightly. This is true because the air-delivering capacity of the pump 27 is sufficient to render a slight amount of leakage around the piston 15 negligible when communication is afforded between ports 23 and 24. Thermostatically controlled valve 105 21 continues to exercise control over the communication between pump 27 and cylinder 14, and correspondingly exercises control over the shutters so long as the engine continues to operate.

In cold weather it is very desirable that the shutters close immediately after the engine is stopped, notwithstanding the fact that the engine may be very hot at the time 110

it is stopped. This operation is assured by the apparatus of my present invention. As soon as the engine stops, the pressure in conduit 31 drops to atmospheric, with the result that valve 30 unseats to permit piston 15 to assume its normal position, and the shutters close under the influence of springs 8 and 17. As soon as the engine is again started, the valve 30 seats, thereby again placing the shutters under the control of the thermostat 19 and its valve 21.

While I have described what I now regard to be a preferred embodiment of my invention, I do not limit myself to the specific 15 construction or arrangement of parts herein shown and described, but claim broadly all other embodiments of my invention as it is defined by the appended claims.

What I claim as new, and desire to secure 20 by Letters Patent of the United States, is:

1. In a shutter attachment unit, the combination of a shell, shutters supported by said shell, an expansible chamber supported by said shell, operating connections between 25 the movable wall of said expansible chamber and said shutters, a thermostatic unit supported by said shell, a conduit connecting with said expansible chamber, a valve actuated by said thermostatic unit and controlling the passage of fluid through said conduit, and an engine-operated fluid pump connected to said conduit.

2. In combination with an engine and its 30 radiator, shutters, spring means tending to close said shutters, an air pressure actuated device adapted when operated to open said shutters against the action of said spring means, an air pump which functions when, and only when, the engine is operating, a passage through which said pump may deliver air to said pressure actuated device, and thermostatic means in contact with the 35 radiator for controlling the flow of air through said passage.

3. In an apparatus of the class described, shutters, a fluid pressure pump which functions when and only when the engine is in operation, a fluid pressure actuated shutter operating device, a passage through which 40 fluid may be delivered from said pump to said device, and a blocking valve responsive to changes in engine temperature interposed in said passage, said shutter operating device receiving all of the displacement of said 45 fluid pressure pump when said valve is open.

4. In an apparatus of the class described, shutters, an air pressure operated device for moving said shutters, an engine operated air pump, thermostatic means for establishing 50 communication between the pump and the air pressure operated device, a vent for said air pressure operated device, and means for closing said vent when the engine is operating.

5. In an apparatus of the class described,

shutters, an air pressure operated device for moving said shutters, an engine operated air pump, thermostatic means for establishing communication between the pump and the air pressure operated device, a vent for said air pressure operated device, and means responsive to air pressure created by said pump adapted to close said vent when the pump is in operation.

6. In an apparatus of the class described, 75 shutters, an engine having cylinders, an air pump connected to receive its pumping impulses from the pressure impulses in one of the engine cylinders, an air pressure operated device for moving said shutters, a passage between said air pressure operated device and said air pump, a thermostat, and a valve controlled by said thermostat adapted to gradually establish and shut off communication between said device and said pump. 80

7. In combination with an engine and its radiator, an air pump operating when and only when the engine is in operation, shutters controlling the flow of air through said radiator, an operating device for said shutters adapted to be actuated by air pressure created by said pump, a passage between said pump and said shutter operating device, a thermostat contacting with the exterior of said radiator responsive to changes in engine temperature, and a valve controlled by said thermostat adapted gradually to open and close said passage. 90

8. In combination with an engine and its radiator, an air pump operating when and only when the engine is in operation, shutters controlling the flow of air through said radiator, an operating device for said shutters adapted to be actuated by air pressure created by said pump, a passage between 100 said pump and said shutter operating device, a thermostat responsive to changes in engine temperature, a valve controlled by said thermostat adapted gradually to open and close said passage, a vent for said shutter operating device, and means responsive to air pressure created by said pump adapted to close said vent when the pump is operating. 110

9. In combination with an engine, means 115 for controlling the flow of air which serves to cool said engine, an air pressure actuated device for operating said air flow controlling means, an air pump adapted to operate when and only when the engine is in operation, a passage affording communication between said air pump and said air pressure actuated device, a valve controlling said passage, a thermostat disposed outside of the cooling circuit and contacting with the radiator for operating said valve. 120

10. In combination with an engine, means for regulating the flow of air which serves to cool said engine, an air pump which operates when and only when the engine is 130

- in operation, an air pressure actuated device for operating said air flow controlling means, a passage affording communication between said pump and said air pressure actuated device, a valve controlling said passage, a thermostat for operating said valve, a vent for said air pressure actuated device, and means responsive to air pressure created by said pump adapted to close said vent when the pump is in operation.
11. In an apparatus of the class described and in combination with an engine and its radiator, shutters for controlling the flow of air through said radiator, spring means normally tending to close said shutters, an air pressure actuated device adapted when operated to open said shutters against the action of said spring means, an air pump associated with one of the cylinders of the engine and operated by variations in fluid pressure within the engine cylinder, a conduit affording communication between said air pump and said air pressure actuated device, a valve controlling said conduit, a thermostat for operating said valve, a vent for said air pressure actuated device, and means responsive to air pressure created by said pump for closing said vent when the pump is in operation.
12. In a shutter attachment unit, the combination of a shell, shutter mechanism supported by said shell, a cylinder supported by said shell, a piston in said cylinder, operating connections between said piston and said shutter mechanism, a thermostatic unit supported by said shell, a conduit connecting with said cylinder, a valve actuated by said thermostatic unit controlling said conduit, and an air pump connected to said conduit, said air pump being connected to receive its pumping impulses from the pressure impulses in one of the engine cylinders.
13. In an apparatus of the class described, shutter mechanism, an expansible chamber operatively connected to actuate said shutter mechanism, a conduit communicating with said expansible chamber, said conduit being adapted to conduct fluid in the operation of said expansible chamber, a thermostatically controlled valve for said conduit, said expansible chamber having one outlet for the fluid contained therein when said valve closes with the engine running, and another outlet for the fluid contained therein when the engine stops.
14. In an apparatus of the class described, shutter mechanism, an expansible chamber operatively connected for actuating said shutter mechanism, a fluid passageway communicating with said expansible chamber, and means responsive to the stopping of the engine for controlling a second fluid passageway communicating with said expansible chamber.
15. In an apparatus of the class described, shutter mechanism, a cylinder, a piston in said cylinder, operating connections between said piston and said shutter mechanism, a fluid passageway communicating with said cylinder, a thermostatically controlled valve for controlling said passageway, said cylinder having a leakage path for venting the same when said valve closes with the engine running, and means responsive to the stopping of the engine for opening a second fluid passageway venting said cylinder.

In witness whereof, I hereunto subscribe my name this 12 day of December, 1923.

JAMES F. RALEIGH.
